CONVERSION OF HYDROCARBONS

Eugene J. Houdry, Woodbury, N. J., assignor to
 Houdry Process Corporation, Dover, Del., a cor-
 poration of Delaware

Application August 31, 1933, Serial No. 687,553

10 Claims. (Cl. 196—52)

This invention relates to the conversion of hydrocarbons into marketable products, both low boiling, such as benzine, gasoline, kerosene, naphtha, etc., and high boiling, such as Diesel oil, domestic fuel oil, etc. In certain respects it may be considered as a further development of or improvement upon the invention set forth in my copending application Serial No. 674,129, filed June 3, 1933, under the title "Treatment 5 of hydrocarbons."

One object of the invention is to reduce the amount of equipment required to effect the desired conversion. Another object is to convert crude starting material in a once through operation without internal recycling of any character. Another object is to effect the conversion 15 at low or atmospheric pressure and with a minimum input of heat. Other objects will be apparent from the detailed description which follows.

The starting material, such as crude oil, topped crude, or the like, is converted in a continuous once through operation into the desired low and high boiling liquids, such as a quality gasoline 25 or motor fuel having a high anti-knock rating and a clean residual oil in the gas oil boiling range. The conversion and/or the treatment of the light product is effected by catalytic and other contact masses arranged for periodical regeneration in situ, so that all tarry constituents and coky deposits are consumed and entirely 30 eliminated from the system during the regenerating periods. The system is arranged for continuous operation without condensation of intermediate products, thus avoiding the necessity for a large number of storage tanks. Pumping equipment is reduced to a minimum by operating the system under pressure not exceeding 40 pounds per square inch, which is little more than 35 that required to send the charge through the apparatus. Usually a single pump in the feed line to the crude oil still is utilized to operate the first fractionating tower under some thirty pounds of pressure which is ordinarily sufficient 40 for the entire system. When the first fractionating tower is operated at substantially atmospheric pressure, additional pumps are needed and are preferably located in some or all of the outlets therefrom. They may be used to advantage when the system includes apparatus for reforming the heavy naphtha with or without the straight run gasoline in order to improve the octane rating of the lighter hydrocarbons.

In order to illustrate the invention and to indicate its operation, concrete embodiments

thereof are shown in the accompanying drawings, in which:

Fig. 1 is a diagrammatic view of a system for converting crude oil;

Fig. 2 is a similar diagrammatic view of a modified system for converting topped crude, treating equipment being omitted; and

Fig. 3 is a diagrammatic view similar to Fig. 1 of a system for crude oil which includes optional equipment for reforming straight run gasoline and heavy naphtha.

In Fig. 1, the charging material, which is crude petroleum or the equivalent, is forced by a pump 3 into a crude oil still 4 of any suitable or desired type, wherein the starting material is 15 partly vaporized and sent with a minimum of cracking into a fractionating tower 5 which is controlled by cooling coil 6. The light hydrocarbon vapors in the boiling range of gasoline and gases leave fractionator 5 by a line 7 which contains a back pressure valve 8 by which a suitable low pressure, normally not exceeding 40 pounds per square inch, is maintained in fractionator 5. A liquid side stream, representing a middle or a deep cut, is withdrawn by a valved line 9 and discharged into a heating coil 10 where the material is again vaporized and raised to a super-atmospheric temperature within the range of 750° to 950° F. and discharged by suitable valved lines into any one of a series of transforming 20 cases, of which two are shown at 11 and 11a, containing catalytic adsorptive material capable of effecting the desired splitting or depolymerizing transformation, such as porous solids, examples of which are certain clays and other materials including floridin, diatomaceous earth, kieselguhr, and silicates of alumina in general. A preferred form of catalyst consists of fragmentary bits or molded pieces of activated hydrosilicate of alumina. The products of the 25 transforming reaction are discharged by suitable valved connections into vapor line 12 which, in turn, discharges into fractionating column 13.

The residuum or bottoms of fractionating tower 5 are withdrawn by a valved line 14 into which steam is discharged in suitable amount by branch line 15, the mixed residuum and steam being discharged by suitable valved connections into any one of a series of contact vaporizers, of which two are shown at 16 and 16a. These vaporizers may be of the type disclosed in United States Patent No. 1,806,997, issued to Alfred Joseph on May 26, 1931, but preferably of the improved type and arrangement disclosed in my copending application, Serial No. 670,954, filed 30 35 40 45 50 55

May 13, 1933, and issued on February 5, 1935, as Patent No. 1,989,927. These chambers contain suitable inert porous contact masses, such as broken fragments of brick, pieces of pumice, molded units of china clay or other silicates of alumina or clayey materials, or preferably the inert carrier material disclosed in United States Patent No. 1,818,403, issued to Alfred Joseph on August 11, 1931. These contact masses act to remove asphaltic or heavy carbonaceous materials, possibly to some extent at least by absorption, leaving the fluids which pass therefrom in vapor form of a more volatile nature than the residuum or bottoms fed thereto. The temperatures ordinarily employed in this contact vaporization are superatmospheric and of the order of 700° to 900° F., or more preferably 790° to 875° F. Often the bottoms introduced into the contact vaporizers can be kept within the desired temperature range without separate heating, except for that supplied by the superheated steam. However, of course it is contemplated to employ a heater where the same is desirable or necessary. The vaporized products from chambers 16 and 16a are discharged by suitable valved connections into line 17 which joins the line leading from heater coil 10 to catalytic transforming chambers 11 and 11a or into separate but like chambers, with the result that all of the liquid products of fractionating tower 5 are subjected to the same catalytic transforming operation, the products of which are discharged into fractionating tower 13. The pressures existing in the vaporizing and transforming operations, because of the nature of the apparatus, are approximately the same as but slightly less than those existing in still 4 and fractionator 5.

The bottoms from tower 13, which consist of a clean residual oil having the characteristics of a gas oil but of either slightly lighter or heavier gravity than the original charging stock, are withdrawn by valved line 18 to storage tank 19. The light overhead hydrocarbons passing control coil 20 leave the top of fractionating tower 13 by a line 21 which joins line 7 carrying the straight run gasoline vapors from fractionating tower 5. A pump or blower (not shown) may be provided in line 21, if needed, to equalize the pressures in lines 7 and 21. All these vapors pass through a heater coil 22 which raises the temperature to the range of 500° to 700° F., and discharges the same through suitable valved connections into any one of a series of catalytic refining chambers, 55 of which two are shown at 23 and 23a. These chambers contain a porous solid composed to substantial extent of components from the group comprising silicates of alumina and clayey materials and may, for example, consist of a molded catalytic material adapted to purify, stabilize, and refine the light hydrocarbons with a polymerizing action and preferably comprising activated hydrosilicate of alumina to which is added small amounts of metallic oxides, such as copper, 60 nickel and cobalt. The refined vapors leave chambers 23 and 23a by suitable valved connections to line 24, which discharges into fractionating tower 25 controlled by cooling coil 26. The liquid polymers thrown down in this column are 65 in the form of a clean residual oil, and are conducted by valved line 26 to residual oil tank 19. The overhead vapors leave fractionator 25 by line 27, which conducts them through condenser 28, and thence into separator 29, whence the fixed 70 gases leave by line 30, while the condensed prod-

ucts, such as gasoline or motor fuel, are conducted by valved line 31 into storage tank 32.

The contact vaporizers 16 and 16a, the catalytic transformers 11 and 11a, and the catalytic refiners 23 and 23a are provided in pairs or multiples thereof, to permit continuous operation of the system, with each member of each group alternately on stream and in regeneration. Regeneration is effected by oxidation, so that all tarry and coky or sulphurous deposits left in any of the contact masses are entirely eliminated during the regenerating periods. The regenerating medium, such as air diluted, as required, with steam or flue gas, may be supplied to contact vaporizers 16 and 16a by valved connections to supply line 33, while the fumes of regeneration are discharged through valved connections to line 34. Similarly, the regenerating medium for catalytic transformers 11 and 11a is provided by supply line 35, while the fumes are discharged into line 36. Line 37 supplies the regenerating medium to the catalytic refining chambers 23 and 23a, the fumes being discharged through line 38.

Much of the apparatus disclosed in Fig. 2 conforms to that shown in Fig. 1, and the same reference characters are applied thereto. The system disclosed in Fig. 2, however, is intended to handle topped crude containing little or no material in the gasoline range. Hence the overhead line 7a from first fractionating tower 5a carries vapors in the gas oil boiling range which pass back pressure valve 8a and are discharged into heater coil 10a which discharges, in turn, into the catalytic transforming cases 11 and 11a. No side stream is withdrawn from fractionator 5a. The bottoms, as in Fig. 1, are withdrawn by valved line 14, and, after being mixed with steam from line 15 and, if necessary, passed through any suitable heater, not shown, are discharged into contact vaporizers 16 and 16a, and thence into the line leading to transforming cases 11 and 11a. The residual oil separated by fractionator 13 goes to storage tank 19, while the overhead vapors and gases are conducted by line 21 to refining apparatus or to storage, as desired.

Fig. 3 discloses a system having all of the features of Fig. 1, with the same reference characters applied to like parts. The new features reside in the means for reforming a naphtha cut from the first fractionator with or without the overhead material or straight run gasoline. Optionally, the straight run gasoline, with or without the heavy naphtha cut, may be separated out and later fed to the refining apparatus, if desired. Fig. 3 also indicates the use of pumps in all of the outlet lines from the first fractionator, provision being made for bypassing each pump so that the entire system may operate under the pressure in the first fractionator maintained by the crude oil feed pump, or, optionally, some or all of the fractions may have further treatment under individual pressure conditions. As indicated, overhead line 1b from first fractionator 5b leads through back pressure valve 8b directly to condenser 38, then through separator 39, from which fixed gas may be withdrawn through a line 40, while the condensed straight run gasoline is passed by line 41 to storage tank 42. A valved line 43, provided, if necessary, with suitable pumping equipment (not shown), connects with heater 22, so that the straight run gasoline may be sent through the catalytic refining apparatus. A heavy naphtha cut is arranged to be withdrawn from the upper part of fractionator 5b by a line 44 which includes a pump 45 having a valved

bypass connection 46 therearound. Line 44 has a valved connection 47 to the overhead vapor line 1b in advance of back pressure valve 8b. Line 47 also includes a pump 48 having a valved bypass 49 therearound. The junction of lines 44 and 47 has a valved connection 50 to a heater coil 51, where the material fed thereto is raised to a temperature within the range of 800° to 950° F. and discharged by suitable valved connections 10 into any one of a series of reforming cases, of which two are shown at 52 and 52a, containing catalytic adsorptive material capable of reforming the heavy naphtha and overhead hydrocarbons from fractionator 5b into light products 15 having an improved antiknock rating. The contact material may consist of molded pieces of inert porous material, or of clayey materials, or silicates of alumina, such as activated hydrosilicate of alumina, containing oxides of one or more of 20 the following metals: vanadium, chromium, tungsten, molybdenum. The reformed vapors from catalytic cases 52 and 52a are discharged through suitable valved connections to line 53 which joins lines 21 and 43 leading to heater 22 of the refining apparatus. A lower liquid side stream representing a middle or deep cut is withdrawn from first fractionator 5b by a valved line 9b leading to heater 10, and thence to the transforming cases 11 and 11a. Line 9b includes a pump 54 having 25 a valved bypass 55 therearound. In a similar manner, the valved outlet 14b from the bottom of fractionator 5b leading to contact vaporizers 16 and 16a includes a pump 56 provided with a valved bypass 57 therearound, the same being 30 located in advance of steam connection 15.

Heaters 10, 10a, 22 and 51 may be of any suitable or desired type, and heat may be supplied from any suitable source to the coils forming a part thereof. If desired, they may consist of separate coils disposed in vaporizing still 4. Since the figures of the drawings are diagrammatic in character, heat exchangers, coolers, and other apparatus not essential to the understanding of the invention, are omitted.

All forms of the invention produce directly from crude starting material, such as crude oil or topped crude, but three final products, namely, (1) a residual oil which is clean and suitable for use directly as Diesel oil or domestic fuel oil, or as superior charging stock for further cracking operations; (2) fixed gases resulting from the transforming operation; and (3) light liquid hydrocarbons, such as motor fuel or gasoline of superior quality and high antiknock characteristics, treated or untreated as desired. With the possible exception of the straight run gasoline, no separation of intermediate products is made, so that tanks for such products and subsequent reheating of the same may be entirely avoided. By operating the first fractionating tower under a very moderate pressure and by effecting the transforming and/or treating operations at low or atmospheric pressure, the requirements for pumping equipment are greatly reduced. If pumps other than that for the charging stock may be needed or required, they are located in the outlet lines leaving fractionator 5, 5a, or 5b, but pumps at such points are ordinarily not necessary, and, if used, may be individually bypassed so that the system has great flexibility of operation. The once through continuous operation to the final products not only conserves heat by reducing the required input, but also greatly simplifies refinery practice in production of high quality finished products. The refining operation

may be omitted when desired without departing from the spirit and scope of the invention.

While the invention has been herein disclosed in what are now considered to be preferred forms thereof, it is to be understood that the invention is not limited to the specific details of such forms, but covers all changes, modifications and adaptations within the scope of the appended claims.

I claim as my invention:

1. The process of transforming high boiling hydrocarbons into lower boiling hydrocarbons in a continuous operation by contacting the same with solid contact materials capable of effecting desirable changes therein which comprises separating the hydrocarbon charge into two fractions of different molecular weights and boiling ranges, the high boiling fraction being composed primarily of heavy hydrocarbons within the fuel oil range and the low boiling fraction being composed substantially of hydrocarbons in the gas oil boiling range, subjecting each fraction to a separate heating operation to effect vaporization, that on the high boiling fraction being effected by contact treatment with a bed of porous contact material, uniting the vapors of both fractions, and subjecting the combined vapors to a transforming operation by the action of active contact material selected from the class consisting of silicates of alumina and clayey material in the temperature range of 750° to 950° F.

2. The process of treating a crude hydrocarbon fluid of petroleum origin to produce a high yield of low boiling hydrocarbons in a continuous operation by contacting the charge with solid contact materials capable of effecting desirable changes therein which comprises separating the hydrocarbon charge into a plurality of fractions of different molecular weights and boiling ranges, subjecting the low boiling fraction to treatment with a bed of porous contact material comprising essentially activated hydrosilicate of alumina and capable of effecting a stabilization of the same, subjecting the other fractions to separate initial heating and vaporizing treatments, each such vaporizing treatment differing from the other and one being effected with a bed of porous contact material, uniting the vaporized fractions, transforming the united fractions in vapor phase by the action of a bed of contact material selected from the class consisting of silicates of alumina and clayey material, and adding low boiling materials from the last named transforming step to the aforesaid low boiling fraction before subjecting the same to treatment by said first bed of porous contact material.

3. The process of treating a crude hydrocarbon fluid made up of various hydrocarbons within a broad range of molecular weights in a continuous operation by contacting the same with beds of solid contact material capable of effecting desirable changes therein including the production of high quality gasoline which comprises separating the hydrocarbon fluid into three fractions of different molecular weights and boiling ranges, subjecting the highest boiling fraction in a continuous stream in succession to contact treatments with three separate beds of contact material under different conditions and separating and removing from the stream the heaviest products after at least one of the first two contact treatments and before the stream passes to the next successive contact treatment, subjecting the intermediate fraction to the last two of said separate contact treatments along with the products of the first fraction by adding the latter to the

stream after the first contact treatment, and subjecting the low boiling fraction to the last of said contact treatments along with the low boiling products from the first two fractions by adding 5 the latter to the stream after the second contact treatment.

4. The process of treating a crude hydrocarbon fluid of petroleum origin containing substantial amounts of components both above and below 10 the gas oil range, as well as within said range, by contacting the same with solid contact materials chosen from the class consisting of silicates of alumina and clayey materials, which comprises the continuous operation of separating the hydrocarbon fluid into a plurality of fractions of 15 different molecular weights and boiling ranges, a low boiling fraction which is lighter than gas oil, a high boiling fraction which is heavier than gas oil, and an intermediate fraction including 20 components in the gas oil boiling range, subjecting each fraction at reaction temperature to an initial contact treatment with a bed of solid contact material from the above class under conditions differing from those of the initial 25 contact treatment of the others, the low boiling fraction being treated under conditions so as to reform the same, the high boiling fraction being treated with a bed of porous but relatively inert material under such conditions as to effect a 30 vaporization of the bulk of the lighter components thereof, so as to produce a composite material of the nature of a crude petroleum oil, the said intermediate fraction being treated under conditions so as to crack substantial amounts 35 thereof into compounds within the gasoline range, and adding products of lower boiling range from each fraction in succession after each contact treatment to the next lighter fraction in advance of a subsequent contact treatment on 40 the same.

5. The process of treating a crude hydrocarbon fluid of petroleum origin by contacting the same with solid contact materials capable of effecting desirable changes therein which comprises separating the hydrocarbon fluid primarily into three fractions of different molecular and boiling ranges, the high boiling fraction having a range above a temperature of the order of 750° F., the low boiling fraction having a boiling range 45 below a temperature of the order of 425° F., and the intermediate fraction having a range intermediate the other two, contacting the said high boiling fraction with a contact material capable of producing therefrom a substantial proportion 50 of hydrocarbons within the range of the aforesaid intermediate fraction and passing the same into the stream of the said intermediate fraction, passing the combined intermediate fraction into contact with a second bed of contact material capable of producing therefrom a substantial proportion of hydrocarbons within the range of the aforesaid low-boiling fraction, separating the hydrocarbons so produced from residual hydrocarbons and passing the same into the stream of the 55 aforesaid low-boiling hydrocarbons, and passing the combined stream of low-boiling hydrocarbons into contact with a contact material composed of an activated hydrosilicate of alumina, capable of stabilizing the same against gum and color formation.

6. The process of treating a crude hydrocarbon fluid of petroleum origin by contacting the same with solid contact materials capable of effecting desirable changes therein which comprises separating the hydrocarbon fluid primarily into three 60 fractions of different molecular and boiling

ranges, the high boiling fraction having a range above a temperature of the order of 750° F., the low boiling fraction having a boiling range below a temperature of the order of 425° F. and the intermediate fraction having a range intermediate the other two, contacting the said high boiling fraction at superatmospheric temperatures with a contact material having a substantial proportion of components from the group comprising silicates of alumina and clayey materials and capable of producing therefrom a substantial proportion of hydrocarbons within the range of the aforesaid intermediate fraction and passing the same into the stream of the said intermediate fraction, passing the combined intermediate fraction into contact with a second bed of contact material having a substantial proportion of components from the aforesaid group and capable of producing therefrom a substantial proportion of hydrocarbons within the range of the aforesaid low boiling fraction, separating the hydrocarbons so produced from residual hydrocarbons and passing the same into the stream of the aforesaid low-boiling hydrocarbons, and passing the combined stream of low-boiling hydrocarbons into contact with a contact material having a substantial proportion of components from the aforesaid group and capable of stabilizing the same against gum or color formation.

7. The process of treating a crude hydrocarbon fluid of petroleum origin by contacting the same with solid contact materials capable of effecting desirable changes therein which comprises separating the hydrocarbon fluid primarily into three fractions of different molecular and boiling ranges, the high boiling fraction having a range above a temperature of the order of 750° F., the low boiling fraction having a boiling range below a temperature of the order of 425° F. and the intermediate fraction having a range intermediate the other two, contacting the said high boiling fraction at superatmospheric temperatures with a contact material composed of a porous, adsorptive solid material from the group comprising silicates of alumina and clayey materials and capable of producing therefrom a substantial proportion of hydrocarbons within the range of the aforesaid intermediate fraction and passing the same into the stream of the said intermediate fraction, passing the combined intermediate fraction into contact with a second bed of contact material composed primarily of an activated hydrosilicate of alumina, capable of producing therefrom a substantial proportion of hydrocarbons within the range of the aforesaid low-boiling fraction, separating the hydrocarbons so produced from residual hydrocarbons and passing the same into the stream of the aforesaid low-boiling hydrocarbons, and passing the combined stream of low-boiling hydrocarbons into contact with a contact material composed of an activated hydrosilicate of alumina, capable of stabilizing the same against gum and color formation.

8. The process of treating a crude hydrocarbon fluid of petroleum origin by contacting the same with solid contact materials capable of effecting desirable changes therein which comprises separating the hydrocarbon fluid primarily into three fractions of different molecular and boiling ranges, the high boiling fraction having a range above a temperature of the order of 750° F., the low-boiling fraction having a boiling range below a temperature of the order of 425° F. and the intermediate fraction having a range intermediate the other two, contacting the said high boiling fraction at superatmospheric temperatures with a contact material having a substantial proportion of components from the group comprising silicates of alumina and clayey materials and capable of producing therefrom a substantial proportion of hydrocarbons within the range of the aforesaid intermediate fraction and passing the same into the stream of the said intermediate fraction, passing the combined intermediate fraction into contact with a second bed of contact material having a substantial proportion of components from the aforesaid group and capable of producing therefrom a substantial proportion of hydrocarbons within the range of the aforesaid low-boiling fraction, separating the hydrocarbons so produced from residual hydrocarbons and passing the same into the stream of the aforesaid low-boiling hydrocarbons, and passing the combined stream of low-boiling hydrocarbons into contact with a contact material having a substantial proportion of components from the aforesaid group and capable of stabilizing the same against gum or color formation.

mediate the other two, contacting the said high boiling fraction at a temperature of the order of 700° to 900° F. with a porous, adsorptive solid material from the group comprising silicates of alumina and clayey materials, thereby to produce therefrom a substantial proportion of hydrocarbons within the range of the aforesaid intermediate fraction, and passing the same into the stream of the said intermediate fraction, 5
10 passing the combined intermediate fraction into contact with a second bed of contact material comprising catalytically activated hydrosilicate of alumina, the temperature of contact being of the order of 750° to 950° F., thereby to produce
15 a substantial proportion of hydrocarbons within the range of the aforesaid low-boiling fraction, and passing the said low-boiling fraction at a temperature of the order of 500° to 700° F. in contact with a refining catalyst comprising a porous hydrosilicate of alumina, thereby to stabilize
20 said fraction against gum and color.

9. The process of converting whole crude hydrocarbon starting material into gasoline, fixed gas, and a clean residual oil in a continuous once-through operation without internal recycling which comprises heating and partly vaporizing the whole crude material without cracking or with a minimum of cracking of the same, passing all the heated material into a fractionating 25 zone and therein continuously separating the same into overhead, at least two side streams, and bottoms, subjecting the upper side stream to a reforming operation in vapor phase in the temperature range of 800° to 950° F. to improve the vaporization and anti-knock characteristics 30 of the lighter hydrocarbons which are in the gasoline boiling range, vaporizing and transforming the lower side stream in the temperature range of 750° to 950° F. in contact with a bed of catalytic material containing a substantial proportion of activated hydrosilicate of alumina, vaporizing the bottoms in contact with a bed of inert absorptive material and adding the resulting vapors to the vaporized lower side stream for transformation thereof in the temperature range of 750° 35 to 950° F. in contact with said catalytic material, fractionating the transformed material from said lower side stream and said bottoms into overhead
40

material in the gasoline boiling range and a clean residual oil having the properties and characteristics of gas oil and Diesel oil, combining the material in the gasoline boiling range from all of the above operations, and refining and stabilizing said combined gasoline material in the temperature range of 500° to 700° F. in contact with a bed of catalytic material which contains activated hydrosilicate of alumina. 5

10. The process of converting whole crude hydrocarbon starting material into motor fuel of the gasoline type, fixed gases, and a clean residual oil without the recovery of any coky or tarry material in a continuous once through operation without any internal recycling which comprises heating and partly vaporizing the whole crude material, passing all the heated material into a fractionating zone and therein separating the same into overhead, at least two side streams and bottoms, subjecting the upper side stream to a reforming operation in vapor phase in the temperature range of 800° to 950° F. to improve the antiknock characteristics of the lighter hydrocarbons, vaporizing and transforming the lower side stream in the temperature range of 750° to 950° F. in contact with a bed of catalytic material comprising or containing activated hydrosilicate of alumina, vaporizing the bottoms in contact with a bed of relatively inert but porous absorptive material and then adding 30 the resulting vapors to the vaporized lower side stream for catalytic transformation with the latter in the aforesaid temperature range of 750° to 950° F., fractionating the transformed material from said lower side stream and said bottoms 35 into overhead material in the gasoline boiling range and a clean residual oil having the properties and characteristics of gas oil or Diesel oil, condensing and combining the lighter hydrocarbons resulting from the above operations to secure a gasoline type motor fuel and to separate therefrom the fixed gases, and regenerating the catalytic masses by oxidation from time to time as required to remove coky and tarry deposits therefrom without interfering with the continuity of the process. 40
